UNITED STATES PATENT OFFICE.

GUSTAVE E. VILLARET, OF LEONIA, NEW JERSEY, ASSIGNOR TO THE PHOENIX GLASS COMPANY, OF PITTSBURGH, PENNSYLVANIA, A CORPORATION OF WEST VIRGINIA.

DESIGN FOR A LAMP SHADE OR SIMILAR ARTICLE.

Application filed November 10, 1925. Serial No. 15,394. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for a Lamp Shade or Similar Article, of which the following is a specification, reference being had to the accompanying drawing, forming a part thereof.

The figure is a side elevational view of the lamp shade made according to my design.

I claim:

The ornamental design for a lamp shade or similar article, as shown.

GUSTAVE E. VILLARET.
